UNITED STATES PATENT OFFICE.

THOMAS ANDERSON, OF WHEELING, WEST VIRGINIA.

HOLDER FOR PAPER NAPKINS.

1,205,073.

Specification of Letters Patent. Patented Nov. 14, 1916.

Application filed June 28, 1915. Serial No. 36,850.

To all whom it may concern:

Be it known that I, THOMAS ANDERSON, a citizen of the United States, residing at Wheeling, in the county of Ohio, State of West Virginia, have invented certain new and useful Improvements in Holders for Paper Napkins; and I do hereby declare the following to be a full, clear, and exact description of the invention, such as will enable others skilled in the art to which it appertains to make and use the same.

The present invention is directed to improvements in holders for paper napkins, and has for its object to so construct a device of this character capable of holding a great number of napkins so that the same may be conveniently withdrawn from the holder one by one.

A further object of the invention is to provide a holder so constructed that the same can be easily and quickly disassembled when necessary to fill the same with napkins.

With these and other objects in view, this invention resides in the novel features of construction, formation, combination and arrangement of parts to be hereinafter more fully described, claimed and illustrated in the accompanying drawing, in which:—

Figure 1 is a perspective view of the device. Fig. 2 is a vertical central sectional view. Fig. 3 is a transverse sectional view through the device. Fig. 4 is a perspective view of one of the compartments.

Referring to the drawing 1 indicates the base, which is preferably formed from sheet metal and is provided with a rectangular recess 2. Rising from opposite sides of the base are sheet metal uprights 3, said uprights having oppositely disposed channels 4 formed therein, the purpose of which will appear later.

A pair of compartments 5 is provided, and consist of front walls 6, side walls 7, and top and bottoms 8 and 9, respectively, all of which are formed from transparent glass. The tops of each compartment are provided with slots 10 which are normally closed by covers 11, which are pivotally supported by the ears 12 carried by the side walls of the compartment, said covers hav-

ing stops 13 carried thereby which are adapted to engage the top so as to limit the swinging movement thereof.

The side walls 7 have their inner edges 55 provided with outturned flanges 14, which are adapted to slidably engage the channels 4 formed in the uprights 3. Thus it will be seen that when the compartments are engaged by the uprights that the same will be 60 disposed in confronting relation, and firmly held against separation, and at which time the lower ends of the compartments will engage the recess 2 formed in the base 1.

Each compartment has formed upon its 65 inner surface, and adjacent the rear edge of the wall 7, bearings 15 which are pivotally engaged by the extensions 16 formed upon the ends of the arms 17 of the wire loops 18, said loops being adapted to bear 70 against the rear side of a package of paper napkins. Since the loops 18 are connected with an elastic band 19 it is obvious that said loops will yieldably engage the package so as to hold the same against the front wall 75 6, and in such a position that the napkins may be removed through the slots 10.

Fixed to the upper ends of the uprights 3 by bolts 20 is a bar 21 which engages the tops 8 of the compartments so as to hold the 80 same against upward movement in the uprights, said bar also serving to support a bell 22.

Spring clips 23 are supported by the sides of the base so that a menu card may 85 be clamped to each side of the holder, as indicated in dotted lines in Fig. 1 of the drawing.

From the foregoing description it will be seen that a holder has been provided so constructed that the same can be placed upon a dining table and will occupy very little space.

What is claimed is:—

A holder of the class described comprising a base, uprights carried by the base, channels formed in the uprights, compartments having their side edges provided with flanges for slidably engaging the channels to hold said compartments in confronting 90 relation, said compartments having slots 100 formed in their tops, covers for normally

closing the slots, a bar engaging the tops of compartments, as and for the purpose set forth. 10
the compartments and having its ends det-
achably engaged with the uprights to pre-
vent accidental upward movement of the
compartments, vertically spaced loops piv-
otally supported in each compartment,
means for holding the loops in yielding en-
gagement with the articles contained in the

In testimony whereof, I affix my signa-
ture, in the presence of two witnesses.
THOMAS ANDERSON.
